PHASE MODULATION

Loy E. Barton, Collingswood, N. J., assignor to
 Radio Corporation of America, a corporation of
 Delaware

Application October 31, 1941, Serial No. 417,385

5 Claims. (CL 179—171.5)

My invention relates to radio transmitters or the like and, particularly, to the art of phase modulating or frequency modulating a carrier wave.

An object of the invention is to provide an improved method of and means for phase modulating or frequency modulating a carrier wave.

A further object of the invention is to provide a simplified circuit for phase modulating the output of a stable oscillator.

A further object of the invention is to provide an improved method of and means for shifting the phase of a carrier wave over a wide angle.

In a preferred embodiment of the invention, the output of a crystal oscillator or the like is applied to the input circuit of a modulating tube through a phase shifting circuit including a condenser and to the plate circuit of the tube through a resistor, the said resistor and the plate to ground capacity of the tube forming a second phase shifting circuit. The first phase shifting circuit introduces an inductive reactance into the plate circuit of the tube since the tube produces a 180 degree phase shift. The negative bias on the modulating tube is adjusted to obtain one-half useful conductance. Upon the application of a modulating signal, if it makes the tube more conducting, the inductive component becomes more effective in shifting the phase of the carrier wave and, if it makes the tube less conducting, the capacitive component becomes more effective. Thus, a maximum phase shift of nearly 180 degrees is possible.

The invention will be better understood from the following description taken in connection with the accompanying drawing in which

Figure 1 is a circuit diagram of one embodiment of the invention, and

Figure 2 is a vector diagram that is referred to in explaining the invention.

Referring to Fig. 1, the invention is shown applied to a radio transmitter in which the carrier wave is produced by a stable oscillator 10 comprising a vacuum tube 11 which has a piezoelectric crystal 12 in its input circuit and a tuned circuit 13 in its plate circuit. A by-pass condenser is indicated at 14.

The modulator tube is shown at 16 as a pentode, by way of example, having a cathode 17, a control grid 18, a screen grid 19, a suppressor grid 21, and a plate 22. The plate to ground capacity of the tube 16 is indicated at C2.

Carrier wave current from the oscillator is fed through a resistor R1 and a condenser C1 which are connected in series with each other between

the plate side of the tuned circuit 13 and ground. The resulting lagging voltage appearing across the condenser C1 is applied through a coupling condenser 26 to the control grid 18 of the modulator tube. Since the tube produces a phase shift of 180 degrees, this voltage appears at the plate 22 as a leading voltage (an inductive component).

Carrier wave current from the oscillator is also fed through a resistor R2 and the plate capacity C2, these two impedances also being in series with each other and connected between the plate side of tuned circuit 13 and ground. Thus a capacitive component appears across C2.

The audio signal or other modulating signal is applied to one of the grids of the modulating tube 16. It preferably is applied to the control grid 18 through grid resistors 27 and 28.

The tube 16 is biased by means of a cathode resistor 29, shunted by the usual bypass condenser 31, to obtain one-half the useful mutual conductance of the tube when no signal is being applied. As shown in Fig. 2, with this adjustment, the reactive voltage E_{c1} produced at the plate 22 of the modulator tube by the voltage drop across condenser C1 balances the reactive voltage E_{c2} produced by current flow through the capacity C2; thus the carrier wave voltage E_r at plate 22 is in phase with the voltage across tuned circuit 13.

30 The action when the modulating signal is applied is as follows: If the signal makes the control grid 18 less negative, the output voltage of the modulator tube decreases and shifts towards E_{r(ind.)}. When the grid 18 is made more negative by the signal, the output voltage also decreases, but shifts towards E_{r(cap.)}. Thus, a limit of a plus or minus 90-degree phase shift is possible.

The linearity of the shift in phase with changes 40 in control grid voltage is determined to a large extent by the proper choice of resistance for resistor R2 and the tube characteristic. In general R2 should have a resistance which is large compared with the reactance of the capacity C. 45 Also, resistor R1 preferably has high resistance compared with the reactance of C1 so that the network R1—C1 will, like the network R2—C2, produce substantially a 90 degree phase shift.

I claim as my invention:

50 1. In combination a source of carrier wave energy having an output terminal, an electric discharge tube comprising an anode that has capacity to ground, a resistor connecting said terminal to said anode, a phase shifting network connected between said source and the input circuit

of said tube, said phase shifting network being designed to produce a phase shift at said anode that is opposite to the phase shift produced thereat by said resistor and said capacity to ground, means for varying the mutual conductance of said tube in accordance with a modulating signal, and means for coupling said anode to a signal transfer circuit.

2. The invention according to claim 1 wherein said tube is adjusted to have at least approximately one-half useful mutual conductance when no modulating signal is being applied.

3. In combination, a source of carrier wave energy, an electric discharge tube comprising a control grid and an anode, said anode having capacity to ground, a resistor connecting said anode to said source at a point above ground potential at the frequency of said carrier wave energy, a second resistor and a condenser connected in series with each other and between ground and said point on said source, said control grid being connected to the junction point of said second resistor and condenser, means for varying the mutual conductance of said tube in accordance with a modulating signal to produce a phase modulated signal at said anode, and means for coupling said anode to a signal transfer circuit.

4. In combination, a stable oscillator having an output terminal, an electric discharge tube comprising a control grid and an anode, said 30

anode having capacity to ground, a resistor connecting said terminal to said anode, a second resistor and a condenser connected in series with each other and between said terminal and ground, said control grid being connected to the junction point of said second resistor and condenser, means for varying the mutual conductance of said tube in accordance with a modulating signal, and means for coupling said anode to a signal transfer circuit.

5. In combination, a stable oscillator having an output terminal at which appears a carrier wave of constant frequency, an electric discharge tube comprising a control grid and an anode, said anode having capacity to ground, a resistor connecting said terminal to said anode and having a resistance which is large compared with the reactance of said capacity at said constant frequency, a second resistor and condenser connected in series with each other and between said terminal and ground, said second resistor having a resistance that is large compared with the reactance of said condenser at said frequency, said control grid being connected to the junction point of said second resistor and condenser, means for varying the mutual conductance of said tube in accordance with a modulating signal, and means for coupling said anode to a signal transfer circuit.

LOY E. BARTON.
